CLAIM

The ornamental design for a light-emitting diode, as shown and described.

DESCRIPTION

FIG. 1 is a top perspective view of a first embodiment of a light-emitting diode showing an upper surface with front and left side surfaces;

FIG. 2 is a bottom perspective view thereof showing a bottom surface with rear and right side surfaces;

FIG. 3 is a front view thereof, a rear view being a mirror image of FIG. 3;

FIG. 4 is a top plan view thereof;

FIG. 5 is a bottom plan view thereof;

FIG. 6 is a left side view thereof;

FIG. 7 is a right side view thereof;

FIG. 8 is a top perspective view of a second embodiment of a light-emitting diode showing an upper surface with front and left side surfaces;

FIG. 9 is a bottom perspective view thereof showing a bottom surface with rear and right side surfaces;

FIG. 10 is a front view thereof, a rear view being a mirror image of FIG. 10;

FIG. 11 is a top plan view thereof;

FIG. 12 is a bottom plan view thereof;

FIG. 13 is a left side view thereof; and,

FIG. 14 is a right side view thereof.

The broken lines shown herein are for illustrative purposes only and form no part of the claimed design.
